STOCKING ANKLE FABRIC

Harry W. Roesener, Philadelphia, Pa., assignor to
Merchantville Hosiery Company, Merchant-
ville, N. J.

Application November 23, 1935, Serial No. 51,186

10 Claims. (Cl. 66—178)

The present invention generally relates to stockings, more particularly to an improved knitted construction for the ankle fabric thereof, and has for one of its main objects the provision of a fabric of the character mentioned adapted to snugly fit the ankle and thus eliminate any bulging or distortion at that point of the stocking when being worn.

Heretofore, it has practically been impossible, with the usual method of knitting, to produce stockings shaped to fully fit at the ankle, because stockings knitted in accordance with known methods lack the ability to fully adapt themselves to the irregular shaped outline of the ankle. It will be understood that since the anatomical structure of the normal human ankle forms posterolateral cavities at the foot joint, the ankle fabric of the stocking lays loosely over said cavities with the result that the fabric does not cling closely to the ankle but bulges out and becomes unduly limp. It is therefore an important object of the invention to provide a knitted stocking having an improved ankle fabric construction wherein are formed shaping panels, one on each of the opposite rear sides of said ankle fabric, and disposed to substantially correspond to the natural cavities at the rear of the ankle, said panels being constructed to lay flat and taut over said cavities, thereby preventing bulging or distortion of the fabric.

Another important feature of the invention resides in the provision of a stocking with a knitted ankle fabric wherein are introduced shaping panels of shortened loops adapted to draw the fabric closely about the ankle of the wearer without, however, being detrimental to the normal elasticity of the major portion of the fabric, which elasticity is necessary for the free movement of the ankle.

Still another important feature of the invention contemplates the provision of a knitted stocking of the full fashioned type having those courses constituting the ankle fabric formed of series of shortened loops spaced by series of plain loops of normal length, said shortened loops in the successive courses being associated to form a panel at each of the opposite rear side portions of the stocking ankle fabric whereby said portions are given a more substantial body for better fitting the ankle of the wearer, without necessitating an increase in the weight of the fabric and without destroying the sheerness thereof, said panels, because of their inherent construction, acting to draw the associated portions of the ankle fabric

tight and flat across the cavities of the wearer's ankle.

It is also among the desirable features of the invention to provide an ankle fabric for knitted stockings having courses consisting of an alternating arrangement of loops of different lengths, the loops of the same length in the successive courses being interlooped in a walewise direction to form alternating panels of different elasticity, cooperating to draw the fabric closely to the ankle while preserving its required elasticity, whereby said fabric may conform itself to the irregular outline of the ankle and yet allow free movement of the same, certain of the loops in the course being transferred to perfect the ankle fit of the fabric.

The invention is further characterized by the method followed in knitting the courses in the ankle fabric of a knitted stocking; by the formation and construction of the courses themselves; and, by the cooperation and correlation of the successive courses to produce ankle shaping panels of predetermined configuration and in certain definite portions of the ankle fabric.

Other important objects and advantages of the invention will be in part obvious and in part pointed out hereinafter.

The method which I prefer to follow in the manufacture of my improved stocking consists in knitting the stocking in the usual way down to the point where the ankle fabric starts, then during the knitting of the courses in said ankle fabric laying the threads on the needles while certain needles are in predetermined position with respect to the sinker bed to form a partial course of loops of conventional length and certain other needles displaced in relation to the sinker bed when predetermined adjacent sinkers come into operation so that the loops formed thereby will be shortened with respect to said loops of conventional length in the course; and finally resuming the usual knitting operation to construct the heel tabs and foot fabric. Also, according to my preferred method, I find it most advantageous when starting the ankle fabric, that is, in the first course of said fabric, to actuate the needles in relation to the sinkers in such a manner that only a very limited number of shortened loops will be incorporated in said first course and then to vary the actuation of the needles as the knitting progresses so as to gradually increase the number of shortened loops in the successive courses. By proceeding in this manner, the associated shortened loops form ta-

pering panels which impart the proper shaping to the ankle fabric.

In order that the invention and the method of carrying the same into practice may be readily understood by those persons skilled in the art, I have, in the accompanying drawings and in the detailed description based thereupon, set out a possible embodiment of the same.

In these drawings:

10 Figure 1 is a fragmentary side elevation of a stocking constructed in accordance with the invention.

Figure 2 is a diagrammatic transversal section illustrating the ankle fit of a stocking having the usual construction.

15 Figure 3 is a view similar to Figure 2, illustrating the ankle fit of a stocking constructed in accordance with the present invention.

Figure 4 is an enlarged diagrammatic view of a 20 fragment of the ankle fabric in a stocking knitted in accordance with the invention.

Figure 5 is an enlarged diagrammatic view of a 25 modified portion of one course in my improved ankle fabric.

Figure 6 is a face elevation of a section of a full fashioned stocking blank embodying the invention.

Having more particular reference to the drawings, wherein like characters of reference designate corresponding parts throughout, I have shown in Figure 1 a knitted stocking 1 having the welt fabric 2, the leg fabric 3, the ankle fabric 4, and the foot fabric 5, the latter including 30 the toe 6, the sole 7, and the heel 8, with its usual high splice portion 8a extending into the ankle fabric 4. The welt, leg, and foot fabrics are of a construction commonly known in the art and, therefore, a detailed description thereof 35 may be dispensed with herein.

According to this invention, the ankle fabric 4, that is, the portion of the stocking substantially included within the area defined by line *a—a* and line *b—b* (Figures 1 and 6) is constituted by courses, portions of which have been 40 diagrammatically shown on an enlarged scale and designated by the reference character 9 in Figure 4. Each course 9 consists of shortened plain loops 10 and plain loops 11 of conventional 45 length. Upon reference to the drawings, it will appear that the shortened loops 10 gradually increase in number in the successive courses for the major portion of the length of the ankle fabric and then decrease in number to assume 50 a configuration adapted to accommodate the formation of the high splice heel portion *a—a* as more clearly illustrated in Figures 1 and 6.

While I have shown in Figure 4 but one set of shortened plain loops 10, it will be understood 55 that in practice each course 9 includes two sets of such shortened plain loops, each set being relatively spaced from one another by a row of plain loops 11 of conventional length and associated with the corresponding set of shortened 60 plain loops in the successive courses to provide a pair of shaping panels, one at each rear side of the stocking ankle fabric 4, as diagrammatically represented in Figure 6.

It is to be noted that the increase in the 65 number of shortened loops 10 in the successive courses is carried in a direction towards the normal rear of the stocking so that the outer border line 13 of the panels 12 starting at a point within the ankle fabric, will extend from wale to wale towards the selvage edges 14 of the full

fashioned stocking blank (Figure 6) or the normal rear portion of the finished stocking 1 (Figure 1), whereas the shortened loops 10 forming the inner border line 15 of the panels 12 are aligned in walewise direction so that said inner border line 15 will extend along a single wale. In this manner, as will clearly appear from the drawings, there is provided at the front of the stocking and between the shortened loop panels 12 a substantially rectangular fabric section 16 10 consisting of loops of conventional length, and at the rear of the stocking, angular fabric sections 17 likewise consisting of loops of conventional length. Because of this construction, it will be appreciated that the fabric sections 16 15 and 17 respectively will cooperate with the panels 12 to impart to the ankle fabric 4 a shape fully conforming to the shape of the wearer's ankle.

Due to the peculiar shaping of the panels 12, the same more readily compensate for the irregularity in the shape of the ankle and because of the special construction of the loops in said panels 12 in relation to the loops in the remaining sections of the ankle fabric, the latter is caused to snugly fit and cling to the ankle. 20 Moreover, since the front section 16 and rear sections 17 are made of loops of conventional length, it will be manifest that said sections retain their normal elasticity and, therefore, free movement of the foot may be had without imposing undue stresses on the fabric structure.

If desired, certain loops in the successive courses may be transferred inwardly of the fabric for the purpose of drawing the same more tightly over the ankle and in Figure 5 of the drawings, I have diagrammatically shown such a course 9a wherein several of the loops 10a are transferred inwardly, several loops 10b are shortened, and the remaining loops 11a in the courses are of conventional length. It will be understood 35 that the transferred loops 10a in the mentioned particular part of the stocking, assist the shortened plain loops 10b to draw the fabric closer to the ankle of the wearer.

The action of my improved construction for the 40 ankle fabric of a knitted stocking will be apparent from a comparison of Figure 3 with Figure 2 of the drawings. In these figures, there is diagrammatically outlined the configuration of a normal human ankle A viewed in transversal cross 45 section. Attention is particularly called to the fact that posterolateral cavities C appear at the ankle. Because of this natural formation, the posterior part of the ankle has a concavo-convex 50 surface with three convex or high point portions P1, P2, and P3, disposed in triangular relationship.

Obviously, in wearing a stocking, the section thereof covering the ankle will bear upon said high points P1, P2, and P3 and, accordingly, a 55 substantial area of the fabric lays loosely over the cavities C with the result that the ordinary fabric becomes unduly limp causing the same to wrinkle or bulge out, as indicated at D in Figure 2. However, when wearing a stocking constructed in 60 accordance with this invention, the shaping panels 12 knitted in the ankle fabric within the area adapted to cover the cavities C draw the fabric close to the surface of the latter and taut across the same, as shown at E in Figure 3, due to the 65 tightening action of the shortened loops forming said panels.

It is to be understood that I do not intend to 70 limit the invention to the particular embodiment described in detail herein, but that I consider 75

within the spirit of the invention any modifications coming within the scope of the sub-joined claims.

What I claim is:

5. 1. In a stocking, an ankle fabric including a pair of shaping panels, one disposed in each of the opposite side portions of said fabric and consisting entirely of shortened loops, and front and rear sections consisting entirely of plain loops of conventional length.
10. 2. In a stocking, an ankle fabric including a pair of shaping panels one disposed in each of the opposite side portions of said fabric and consisting entirely of shortened plain loops, and front and rear sections consisting entirely of plain loops of conventional length.
15. 3. In a stocking, an ankle fabric comprising a pair of shaping panels one disposed in each of the opposite side portions of said fabric and consisting entirely of shortened loops, and front and rear sections consisting entirely of loops of conventional length, certain of said loops in the rear section being transferred to extend from one wale to another wale in the fabric.
20. 4. In a stocking, an ankle fabric including series of successive courses, each successive course having two sets of shortened loops, one set being disposed at each of the opposite rear side portions of the ankle fabric and said sets of shortened loops in the successive courses being associated to form a panel of closely drawn fabric extending walewise of the ankle fabric in each of the mentioned portions.
25. 5. In a stocking, an ankle fabric including series of successive courses, each successive course having two set of shortened loops, one set being disposed at each of the opposite rear side portions of the ankle fabric and said sets of shortened loops in the successive courses being 30 associated to form a panel of closely drawn fabric extending walewise of the ankle fabric in each of the mentioned portions, the number of shortened loops in each set of every course gradually
35. increasing in walewise direction towards the normal rear of the fabric.
40. 6. In a full-fashioned knitted stocking, an ankle fabric including series of successive courses, each successive course consisting of shortened loops and loops of conventional length, said shortened loops in the series of successive courses being associated and interlooped to form a panel of closely drawn fabric extending walewise of the ankle fabric at each of the opposite rear side 45 portions thereof, certain of said loops of conventional length being transferred from one wale to another wale in the ankle fabric to draw the same closely to the ankle of the wearer.
45. 7. A knitted stocking ankle fabric having a 50 pair of shaping panels one disposed in each of the opposite side portions of said fabric and consisting entirely of loops knitted tighter than the loops in the fabric about said panels.
50. 8. In a knitted stocking ankle fabric, a pair of 55 knitted shaping panels, one disposed in each of the opposite side portions of said fabric and each panel being knitted tighter than the surrounding fabric.
55. 9. In a knitted stocking ankle fabric, a plurality of courses, each of said courses having two 60 relatively spaced sets of loops knitted tighter than the intermediate loops in the course, one set being disposed at each of the opposite side portions of the ankle fabric and the sets of loops 65 within each of said portions being associated to form therein a panel of closely drawn fabric.
60. 10. In a knitted stocking ankle fabric, a plurality of courses, each of said courses having two 70 relatively spaced sets of loops knitted tighter than the intermediate loops in the course, one set being disposed at each of the opposite side portions of the ankle fabric, the sets of loops within each 75 of said portions being associated to form therein a panel of closely drawn fabric, and certain of said intermediate loops in the courses being transferred from one wale to another.

HARRY W. ROESENER.
